(57) **CLAIM**

The ornamental design for a strap connector set, as shown and described.

DESCRIPTION

FIG. 1 is a front elevation view of a first component of the strap connector set, showing my new design, in which the rear elevation view is a mirror image thereof;

FIG. 2 is a top plan view thereof;

FIG. 3 is a side elevation view thereof, the right and left side elevation views being mirror images of each other;

FIG. 4 is a front elevation view of a second embodiment of the strap connector set showing my new design, in which the rear elevation view is a mirror image thereof;

FIG. 5 is a top plan view thereof;

FIG. 6 is a side elevation view thereof, the right and left side elevation views being mirror images of each other;

FIG. 7 is a bottom plan view thereof;

FIG. 8 is a front elevation view of a third component of the strap connector set, showing my new design, in which the rear elevation view is a mirror-image thereof;

FIG. 9 is a bottom plan view thereof;

FIG. 10 is a top plan view thereof;

FIG. 11 is a left side elevation view thereof;

FIG. 12 is a right side elevation view thereof;

FIG. 13 is a front elevation view showing the strap connector set as assembled from the first, second and third components in an assembled configuration; and,

FIG. 14 is a rear elevation view thereof.

Broken lines are used in the figures to represent portions of the article that are not claimed. The intermittent cross-hatched patterns are meant to represent a contrast in material.

FIGS. 4, 6, 13 and 14 contain symbolic breaks in the length of the article in which the claimed design is embodied. The appearance of any portions of the article between the broken lines directly adjacent to the shaded regions forms no part of the claimed design.

1 Claim, 4 Drawing Sheets
